UNITED STATES PATENT OFFICE

165,362

SEWING-MACHINE HEAD

Robert D. Budlong, Evanston, Ill., assignor to New Process Gear Corporation, Syracuse, N. Y., a corporation of Delaware

Application May 23, 1951, Serial No. 15,293

Term of patent 14 years

(Cl. D70—1)

To all whom it may concern:

Be it known that I, Robert D. Budlong, a citizen of the United States of America, and resident of Evanston in the county of Cook and State of Illinois, have invented a new, original, and ornamental Design for a Sewing-Machine Head, of which the following is a specification, reference being had to the accompanying drawings, forming a part thereof.

In the drawings:

Figure 1 is a front elevation of the sewing-machine head showing my new design;

Figure 2 is a left end elevational view thereof;

Figure 3 is a rear elevation thereof; and

Figure 4 is a right end elevational view thereof.

Parts of the sewing machine below the level of the work supporting base are shown, in all the figures of the drawings, in broken lines, said parts forming no part of my new design.

I claim:

The ornamental design for a sewing-machine head, substantially as shown and described.

ROBERT D. BUDLONG.
